INVENTOR

ATTORNEY

UNITED STATES PATENT OFFICE.

ERASTUS H. BENN, OF WATCH HILL, RHODE ISLAND.

TIE.

1,390,190.

Specification of Letters Patent. Patented Sept. 6, 1921.

Application filed April 19, 1921. Serial No. 462,639.

To all whom it may concern:

Be it known that I, ERASTUS H. BENN, a citizen of the United States, residing at Watch Hill, in the county of Westerly and 5 State of Rhode Island, have invented new and useful Improvements in Ties, of which the following is a specification.

This invention relates to a metal tie for railways, the principal object of the invention being to provide a tie of great strength and one which can be manufactured at low 10 cost.

Another object of the invention is to provide a laminated tie of channel construction 15 and provided with means for securing the rails thereto.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a plan view of a tie made in 30 accordance with my invention.

Fig. 2 is an elevation showing the rails thereon.

Figs. 3, 4 and 5 are end views showing how the tie is made.

As shown in these views the tie 1 is of 35 channel shape in cross section with its flanges depending downwardly and the rails 2 resting upon the bight and being secured thereto by bolts 3. Instead of these bolts I may

form tongues in the tie to engage the rails or 40 said rails may be secured to the tie in any other suitable manner.

The tie is formed of sheet metal which has its edge portions bent over upon its center portion to provide a body formed of three 45 thicknesses of metal, as shown in Figs. 3 and 4. The side portions of this body are then bent at right angles to provide a channel-shaped member, as shown in Fig. 5. Thus a tie of great strength is produced and 50 one which can be manufactured at low cost. The tie may be provided with the holes 4 for receiving the rail attaching bolts.

It is thought from the foregoing description that the advantages and novel features 55 of my invention will be readily apparent.

I desire it to be understood that I may make changes in the construction and in the combination and arrangement of the several parts, provided that such changes fall within 60 the scope of the appended claims.

What I claim is:—

1. A tie of the character described comprising a body formed of several thicknesses of sheet metal with its side portions bent at 65 right angles to its central portion to produce a laminated tie of channel shape in cross section.

2. The herein described process of forming a tie consisting in folding the side portions of a sheet of metal upon the center portion to secure a body of three thicknesses of metal and then bending the side portions of said body at right angles to form a channel shaped tie. 70

In testimony whereof I affix my signature.

ERASTUS H. BENN.
